Tenyon Sterryon

UNITED STATES PATENT OFFICE.

STEPHEN D. BAKER, OF NEW YORK, N. Y.

DESIGN FOR A BATHROOM BRACKET OR HOOK.

Application filed December 31, 1921. Serial No. 526,391. Term of patent 14 years.

To all whom it may concern:

Be it known that I, STEPHEN D. BAKER, a citizen of the United States, and a resident of New York city, in the county of New York and State of New York, have invented a new, original, and ornamental Design for a Bathroom Bracket or Hook, of which the following is a specification, reference being had to the accompanying drawings, forming part thereof.

In the drawings:

The single figure is a perspective view of a bathroom bracket or hook embodying my new design.

I claim:

The ornamental design for a bathroom bracket or hook as shown.

STEPHEN D. BAKER.
